PIANO

Arthur H. Morse and Armand F. Knoblaugh,
Cincinnati, Ohio, assignors to The Baldwin
Company, Cincinnati, Ohio

Application June 24, 1937, Serial No. 150,191

6 Claims. (Cl. 84—240)

Our invention has reference to upright pianos of reduced height, in which the striking and damping mechanism, conveniently called the action, is located at least partly below the key-board level. In these pianos means must be provided for transferring the motions of the keys downward to the action. The present invention pertains to improvements in these transferring means, in co-ordination with the other operative parts, and in this we have in mind not only the improved operations of the instruments for the production of music but facility in their manufacture and repair.

It is a primary object of the invention to provide operative connections between the keys and action of a compressed upright piano whereby these connections may be manufactured and assembled into a unit for all the notes, quite independent of the rest of the piano, and then installed as such in the instrument, just as the keyboard and action assemblies are installed in the process of constructing an upright piano.

A second object of the invention is to provide a motion transmitting assembly that, being installed in the piano, the addition of the action assembly to the piano automatically establishes operative connections between these two assemblies, note for note of the instrument.

A third object is to provide a motion transmitting assembly so that the installation of it and the keyboard in the piano, as two independent units automatically establishes operative connections between these, note for note.

A fourth object of the invention is to provide a simple means such that the motions of the rear ends of the keys are transferred to the action in the same amounts and direction, directly without amplification or reduction and without intermediate levers.

It is seen that the attainment of the above objects provides that the operation of the piano is complete as an incidental to its assembly, requiring but minor adjustments, thereby achieving facility and lowered cost in manufacture and repair. Moreover, the means for operatively connecting the keys and action may be an independently pre-assembled, completed unit for all the notes, as are the action assembly and keyboard in conventional upright piano manufacture. Furthermore, simple and direct connecting means are thereby provided.

Other objects are:

To provide conventional keys which may be pivoted intermediate of their ends, which may carry conventional regulating means in their rear

portions, preferably the familiar capstan screws, and which may be removed and replaced individually in the well-known manner.

To provide an action which may be identical with that of a conventional upright piano, in particular requiring no changes in the wippines, and which may be removed, adjusted, repaired, and installed, quite independent of the motion transmitting assembly, exactly as is a conventional upright action.

To provide an economy of parts, particularly whereby the motion transmitting assembly may be supported on brackets, these brackets serving as bearings for the action brackets.

To provide an arrangement requiring small space so as not to disturb the appearance of the piano.

The manner in which these objects are attained, and the attainment of other objects which may occur to those reading this specification, is clearly shown in the following description and drawing which form a part hereof. In the drawing,

Figure 1 is a fragmentary side view of the piano of our invention, showing for convenience only those parts essential thereto. (The damper mechanism, for instance, and the front part of the key have been omitted in the interest of clarity and to permit a larger drawing);

Figure 2 is a side view, slightly enlarged, of the connecting link forming part of our invention;

Figure 3 is a top view of the link of Figure 2 (and Figure 1);

Figure 4 is a top view of an upper guide rail; and

Figure 5 is a top view of a lower guide rail.

With reference to Figure 1, a compressed upright piano includes a keybed 1 and a structural back 2 which may be united by side arms (not shown) in any of the known ways. The back 2 supports a soundboard 3 and string plate 4 in a conventional manner. A number of vibratory strings such as 5 are tensioned on the plate 4 to co-operate with the board 3 in the production of sound. On the upper surface of the keybed 1 is a keyboard including a plurality of immediately pivoted keys as 6.

A motion transmitting assembly 7 includes an upper rail 8, a lower rail 9, a plurality of nearly vertical translatory links 10, and brackets 11. Of the brackets 11 there may be a convenient number, of which we prefer four at suitable spacing, and these are screwed to the underside of the keybed 1 so as to project rearwardly, downwardly, and upwardly therefrom. Rails 8 and 9 are sup-

ported by the brackets 11, as shown, and may extend substantially the inner length of the piano. As is displayed, the rail 8 is supported above the rear part of the bed 1 while rail 9 is below and located somewhat rearwardly thereof.

The rails 8 and 9 serve as guides for the translatory links 10, of which there are as many as notes in the piano. The rail 9 contains a plurality of holes 12 (Figure 5) in which the lower 10 cylindrical portions of the links 10 are guided, while the upper rail 8 has corresponding slots 13 (Figure 4) for guiding the upper flattened portions of these links and preventing the swiveling thereof. A cap strip 14 is provided for this upper 15 rail.

Now it will be seen that in keeping with the spirit of this invention and its objects, the assembly 7 comprising the rails 8 and 9, links 10 and brackets 11 may be completed quite independent of the piano and installed therein by merely screwing the rail-spaced brackets 11 to the underside of keybed 1.

Located generally to the rear of the assembly 7 is a conventional upright action assembly 15, integrated on rails and brackets as 16. The action 15 is attached to the piano back 2 by convenient bolts 17, while bearing is provided for the action by vertical screws 18, operated in the brackets 11 and extending into recesses in the 30 under sides of the brackets 16. The screws 18 are provided with lock nuts 19.

Each link 10 is formed from a cylindrical metal rod and includes an S-shaped bend just above its lower guided part. With the assembly 7 in place in the piano, the locating of the action 15 in the instrument automatically establishes an operative connection between the action and the motion transmitting assembly, each conventional wippen 20 resting on the upper section of the S-bend of the corresponding link 10. The lower section of each S-bend, for adapting the link around and upwardly in front of the action, is widened by flattening, for strengthening purposes. It is evident from the disclosure that the 45 conventional action assembly 15 may be removed and installed as is the action of a conventional upright piano.

Just below the upper guided part on each link 10, is formed a horizontal, forwardly extending 50 shelf 21. This, when the keyboard is installed in the piano, rests on the capstan screw 22 in the rear part of the corresponding key 6 to establish automatically an operative connection between the key and the link.

Certain features of the link 10 are not novel 55 in this disclosure; we refer to a copending application Serial No. 125,771, filed by Arthur H. Morse, one of the present applicants, in the United States Patent Office, on February 15, 1937, for a Piano key and action connection.

It will be seen that in the operation of the piano of our invention the links 10 transfer the motions at the rear of the keys 6 in the same amounts and direction to the under sides of the 65 wippens 20 as these motions are transferred in conventional upright pianos. Thus, the downward motion of the front part of a key 6 raises the rear part; the capstan screw 22 attacks the shelf 21 and impels the link 10 into translatory, 70 nearly vertical motion; and the motion of the link motivates the wippen 20, thus causing the action to operate upon the hammer 23, striking the string 5 to produce a piano tone.

It is desired that the above disclosure be exemplary and not restrictive, for modifications

may be made in our invention without departing from the spirit thereof. Having thus described our invention, we claim:

1. An upright piano including a key bed, a keyboard comprising a plurality of keys supported on said key bed, an action located to the rear of said keys and at least partially below the level thereof, bracket means supported on said key bed and having rearwardly disposed portions extending both upwardly from and downwardly from said key bed, a rail supported on said bracket means above said keys, a second rail supported on said bracket means below said keys, each of said rails having transverse apertures therein, and a plurality of elongated motion transmitting members having end portions moving in and guided by the apertures in said rails respectively, said motion transmitting members having means intermediate their ends and located near said lower rail for transmitting motion to said action and having means intermediate their ends and located near said upper rail for receiving motion from said keys, said last mentioned means comprising rigid arms extending from said motion transmitting members in a direction to overlie the ends of said keys and to be contacted thereby for motion transmitting purposes at points interspaced from the axes of said motion transmitting members. 30

2. An upright piano including a key bed, a keyboard comprising a plurality of keys supported on said key bed, an action located to the rear of said keys and at least partially below the level thereof, bracket means supported on said key bed and having rearwardly disposed portions extending both upwardly from and downwardly from said key bed, a rail supported on said bracket means above said keys, a second rail supported on said bracket means below said keys, each of said rails having transverse apertures therein, and a plurality of elongated motion transmitting members having end portions moving in and guided by the apertures in said rails respectively, said motion transmitting members having means intermediate their ends and located near said lower rail for transmitting motion to said action and having means intermediate their ends and located near said upper rail for receiving motion from said keys, said last mentioned means comprising rigid arms extending from said motion transmitting members in a direction to overlie the ends of said keys and to be contacted thereby for motion transmitting purposes at points interspaced from the axes of said motion transmitting members, the apertures in at least one of said rails being non-symmetrical in cross section and the corresponding end portions of said motion transmitting members being shaped to conform to said apertures, whereby twisting of said members in said apertures is prevented for the purpose of maintaining the alignment of said motion transmitting members and said keys and action respectively. 55

3. In a motion transmitting assembly for a piano having an action with wippens and a key bed assembly including keys, the combination of bracket means attachable to said key bed and having portions extending behind said key bed in both upwardly and downwardly directions, a rail attached to the upwardly extending portions of said bracket means so that said rail lies above said keys, a rail attached to the downwardly extending portions of said bracket means so that 70

5 said rail lies below said keys, and motion transmitting members having end portions journaled for purely axial longitudinal movement in apertures in said rails respectively, said motion transmitting members having rigid abutment means intermediate their ends near the upper portion thereof extending forwardly over said keys whereby to receive the motion of said keys, and rearwardly extending abutment means intermediate their ends and positioned to underlie said wippens whereby to impart the motion of said keys to said wippens, the said motion transmitting assembly being otherwise independent of said keys and said wippens, and unitary in structure whereby it constitutes a structure which may be separately removed without disturbing the relationship of the action and the keys.

10 4. A motion transmitting assembly as set forth in claim 3 including means for preventing an axial twisting motion of said motion transmitting members, whereby the alignment of said extensions is maintained.

15 5. An upright piano including a key bed, a keyboard comprising a plurality of keys supported on said key bed, an action located to the rear of said keys and at least partially below the level thereof, a rail supported above the rear ends of said keys, a second rail supported below the rear ends of said keys, each of said rails having transverse apertures therein, and a plurality of elongated motion transmitting members having end portions moving in and guided by the apertures in said rails respectively, said motion transmitting members having means intermediate their ends and located near said lower rail for transmitting motion to said action and having means intermediate their ends and located near said upper rail for receiving motion from said keys, said last mentioned means com-

20 prising rigid arms extending from said motion transmitting members in a direction to overlie the ends of said keys and to be contacted thereby for motion transmitting purposes at points interspaced from the axes of said motion transmitting members.

25 6. An upright piano including a key bed, a keyboard comprising a plurality of keys supported on said key bed, an action located to the rear of said keys and at least partially below the level thereof, a rail supported above the rear ends of said keys, a second rail supported below the rear ends of said keys, each of said rails having transverse apertures therein, and a plurality of elongated motion transmitting members having end portions moving in and guided by the apertures in said rails respectively, said motion transmitting members having means intermediate their ends and located near said lower rail for transmitting motion to said action and having means intermediate their ends and located near said upper rail for receiving motion from said keys, said last mentioned means comprising rigid arms extending from said motion transmitting members in a direction to overlie the ends of said keys and to be contacted thereby for motion transmitting purposes at points interspaced from the axes of said motion transmitting members, the apertures in at least one of said rails being nonsymmetrical in cross section and the corresponding end portions of said motion transmitting members being shaped to conform to said apertures, whereby twisting of said members in said apertures is prevented for the purpose of maintaining the alignment of said motion transmitting members and said keys and action respectively.
